UNITED STATES PATENT OFFICE

2,160,988

HOLDING INSTRUMENT

Lester H. Reineke, New Haven, Conn.; dedicated
to the free use of the People of the United
States

Application October 15, 1936, Serial No. 105,800

4 Claims. (CL. 88—40)

(Granted under the act of March 3, 1883, as
amended April 30, 1928; 370 O. G. 757)

This application is made under the act of
March 3, 1883, as amended by the act of April
30, 1928, and the invention herein described, if
patented, may be manufactured and used by or
5 for the Government for governmental purposes
without the payment to me of any royalty thereon.

I hereby dedicate the invention herein de-
scribed to the free use of the public in the terri-
10 tory of the United States of America to take effect
upon the granting of a patent to me.

This invention relates to means whereby incre-
ment cores (cylindrical cores of wood of small
15 diameter and variable length, extracted from
trees with a hollow auger of special design by
boring radially into the tree trunk and perpen-
dicularly to its long axis) may be held without
breaking while cutting two flat faces parallel to
20 the axis of the core and perpendicular to the
grain of the wood, reducing the thickness of the
increment core to reduce its opacity to light, and
transmitting light through the core while held in
the device, to render discernible for counting and
25 measuring, growth rings which are indiscernible
by reflected light because of the character of the
wood.

I attain these objects by the device illustrated
in the accompanying drawing in which—

Figure 1 is a top plan view of the device; Figure
30 2 is a section through AA of Figure 1; Figure
3 is a side elevation of the device; Figure 4 is an
end view thereof; and Figure 5 is a view in iso-
metric perspective of the device with a modified
35 form of microscope and illuminating means at-
tached thereto.

Similar numbers refer to similar parts through-
out the several views.

The invention consists in an arrangement of
40 two plates 1 and 2 of a thickness less than and
preferably $\frac{1}{2}$ to $\frac{3}{5}$ the diameter of the core 3
to be used in the device, the thickness of the
plates to equal the thickness to which the core is
to be reduced, said plates suitably constrained by
45 loop guides 4 to move with their surfaces in the
same plane with respect to each other, with edges
5 and 6 constrained by taper guides 7 within the
loop guides 4, and tapered edges 8 of plate 1, or
other suitable means to move parallel to each
50 other, forming a gap of variable width, prefer-
ably from $\frac{3}{5}$ to $1\frac{1}{2}$ times the diameter of the in-
crement cores to be used. Plate 2 is rigidly se-
cured at the ends thereof within loop guides 4
while plate 1 is adapted to move frictionally with-
55 in loop guides 4. The latter construction may be
altered of course by securing one guide to one

plate and the other guide to the second plate.
Either assembly is equally effective.

Edges 5 and 6 are provided with grooves 9 or
other suitable means for positioning the core cen-
trally with equal amounts of the core projecting 5
beyond each surface of plates 1 and 2, and for
preventing bending, twisting, or rotating of the
core during subsequent manipulation, and one
edge 5 of plate 1 is provided with a stop 10 against
which one end of the core abuts, said stop pre- 10
venting sliding of the core as a cutting edge is
drawn toward it when removing the projecting
portions of the core. Plate 1 bearing stop 10 may
be graduated along edge 5 with a suitable scale 13
or scales on either or both surfaces of plate 1 15
beginning at stop 10. The device may be
equipped with a magnifying glass 11 so mounted
as to be in focus with the surface of plates 1 and
2, centered over the gap between edges 5 and 6,
movable over the length of the device and remov- 20
able therefrom to avoid interference with the
operation of the cutting edge when cutting the
faces of the core. The device may be equipped
also with a light source 12 attached to and mov-
ing with the magnifying glass support on the side 25
of plates 1 and 2 opposite to that of the magni-
fying glass and so arranged that its light will be
directed to the magnifier through the core in the
gap between edges 5 and 6. As used by me the
light source is supported in the above prescribed 30
position on the plates 1 and 2 by a paraboloidal
shell or housing 14 which serves as a support to
the light source and also acts as a reflector. The
magnifying glass is supported in the above pre-
scribed position by the tubular member 15 which 35
also serves as a hood to shield the core 3 from ex-
traneous light. As indicated above, the magni-
fying glass and light source should be movable
over the length of the device and removable
therefrom. While this may be accomplished in 40
any convenient way without departing from the
spirit of the invention, I accomplish this object
in the manner disclosed in the drawing by at-
taching the shell 14 to the tubular member 15 at
a point adjacent to the outside longitudinal edge 45
of plate 1 by means of guide member 16, the in-
wardly extending arms of which frictionally en-
gage both sides of plate 1. The member 14 is at-
tached to the bottom of the channel member 16
and the member 15 is attached to the top of the 50
channel member 16 by any suitable means. The
light source 12 is positioned within shell 14 in
alignment with the core 3 when the core is con-
fined between plates 1 and 2. The magnifying
glass 11 is positioned within the tubular member 55

13 in focus with the increment core space. The inner edges of shell 14 and tubular member 15, not attached to each other as above indicated, are in sliding contact with the adjacent surfaces 5 of plates 1 and 2. Said light source may extend the full length of the device as shown in Figure 5. In this figure an elongated source of light 17 is carried within a housing 18. Said housing, instead of being secured to the channel 16, extends the full length of the device and it is removably attached thereto by clips 19, 19 secured to the ends of said housing 18, said clips clamping over the guides 4, 4, substantially as shown.

In operation, plates 1 and 2 are placed in the 15 position of maximum gap between edges 5 and 6, the core is placed within the gap with one end against stop 10, with the grain of the wood perpendicular to plates 1 and 2 and with equal amounts of the core projecting beyond each surface of plates 1 and 2. Edges 5 and 6 are then 20 made to approach each other through the action of taper guides 7 and tapered edges 8 when plate 1 is moved in the appropriate direction through guides 4, thus holding the core between edges 5 and 6. Edges 5 and 6 should not exert excessive 25 pressure on core 3 as such excess pressure will resist sliding of core 3, thereby inducing localized tensile stresses in the core behind the cutting edge, resulting in breakage of the core. The 30 compression stresses in advance of the cutting edge do not damage the core and are absorbed by stop 10. The grooves 9 in edges 5 and 6 straighten and center the core 3 so that said core projects equally beyond both surfaces of plates 35 1 and 2, and the lips of grooves 9 cut into the core sufficiently to prevent rotation of the core during the cutting operation. The projecting portions of the core are then removed with a knife or other suitable tool drawn toward stop 10, reducing the 40 thickness of the core to that of plates 1 and 2. Light is then transmitted through the core from a suitable light source 12 and the annual growth rings may be examined, counted, or measured 45 with the scale along edge 5, using magnifier 11 if desired. By transmitted light, growth rings which are not discernible by reflected light become visible distinctly.

Having fully disclosed my invention, I claim:

1. A device of the character described comprising a pair of flat plates positioned longitudinally, parallel and adjacent to each other, edge to edge, in the same plane, the plates having coextensive

grooves along said adjacent edges adapted to receive an increment core, such core being held by the edges of the plates, means to maintain the plates adjustably in such plane and means to control the separating movement of the plates from each other. 5

2. A device of the character described comprising a pair of plates positioned longitudinally parallel and adjacent to each other, edge to edge, in the same plane, the plates having coextensive 10 grooves along said adjacent edges adapted to receive an increment core and one of the edges having a stop against which said increment core may abut, plate guides inclosing the plates and rigidly attached to one of said plates adjustably 15 to maintain said plates in such plane and taper guides within the plate guides to control the outward movement of the other plate, said last mentioned plate having tapered sections to conform to the taper guides. 20

3. A device of the character described comprising a pair of plates positioned longitudinally parallel and adjacent to each other, edge to edge, in the same plane, the plates having coextensive 25 grooves along said adjacent edges adapted to receive an increment core and one of the edges having a stop against which said increment core may abut, plate guides inclosing the plates and rigidly attached to either of said plates to maintain said plates adjustably in such plane and taper guides 30 within the plate guides to control the separating movement of the plates, said plates having tapered sections to conform to the taper guides. 35

4. A device comprising a pair of plate-like thickness gauges and cutter guide surfaces positioned longitudinally parallel and in adjustable proximity to each other, edge to edge, in the same plane, the plates having coextensive grooves along said adjacent edges, means adjustably to maintain the plates in the same plane and means 40 to control the separating movement of the plates from each other, said plates to support and guide an intermittently applied cutting edge and regulate to predetermined dimension the limit of cutting thereby, adjustable tubular and shell means 45 on opposite sides of the surfaces of the plates and supported thereby and in alignment with a line between said grooved edges, a magnifying glass and light source positioned within said adjustable tubular and shell means, respectively. 50

LESTER H. REINEKE.
